UNITED STATES PATENT OFFICE

1,953,059

COLLAPSIBLE BOAT

Alfred Berendt, New York, N. Y.

Application December 8, 1932, Serial No. 646,252

1 Claim. (Cl. 9—2)

One object of this invention is the provision of a novel collapsible boat adapted for use around summer resorts where a sufficient amount of water is available for boating, the boat being formed of a number of sections which may be dismantled and the sections stacked together, in order to provide a compact package which may be conveniently carried about by a person without requiring a vehicle or other means of transportation.

Another object of the invention is to provide a collapsible boat comprising a hollow frame forming the outline of the boat and having a plurality of buoyant cushion-like floats secured at various points on the frame to give the boat its buoyancy, the floats being so constructed as to make overturning of the boat practically impossible.

Still another object of the invention is the provision of novel means for mutually interlocking the various sections of the frame.

A still further object is the provision of a sectional paddle adapted to be used to propel the boat and formed of a plurality of removable sections, so that the dismantled paddle may be conveniently carried about.

The above and other objects will become apparent in the description below, in which characters of reference refer to like-named parts in the drawing.

Referring briefly to the drawing, Figure 1 is a plan view of the boat.

Figure 2 is a side view of the same.

Figure 3 is a cross-sectional view taken on line 3—3 of Figure 1.

Figure 4 is a cross-sectional view of one end of a frame section.

Figure 5 is a cross-sectional view, with the intermediate portion omitted, of a frame section.

Figure 6 is a plan view of the mutually adjacent ends of a pair of frame sections.

Figure 7 is a view of two sections, one shown fragmentarily, of the paddle.

Figure 8 is an enlarged cross-sectional view taken on the line 8—8 of Figure 7.

Referring in detail to the drawing, the numeral 10 represents the complete metal frame of the boat which is squared at the rear end and curved at the forward end, in conformity with the practice of boat construction. The rear frame member 11 is formed in substantially U-shaped conformation, and the front frame member 12 in substantially V-shaped conformation. The frame throughout this boat is made of hollow piping or the like. Connected to one of the sides

of the U-shaped frame member 11, is a frame section 14, a second frame section, and a third frame section 16 which is also connected to the frame section 12. The other side of the frame section 11 is joined by means of sections 13, 17, 60 and 15, to the section 12. An air-inflated cushion or the like 19, is suspended from the frame section 11 by means of rings 24. This cushion together with similar cushions 20 and 21 may be formed of a casing of rubber and equipped with the usual inflating valve (not shown). For purposes of appearance the rubber casing of these cushions may be covered with canvas which may bear appropriate designs. At the forward end, the rear cushion 19 is hollowed out as shown at 22 70 to provide a curved back rest for the occupant seated on the seat 25. The central cushion 20 is likewise hollowed out at 23. Between the cushions 19 and 20 a seat 25 is suspended from opposite frame sections 13 and 14. This seat 75 comprises a wide strip of canvas or the like having its ends 26 sewed on to the frame section 13 and 14, or otherwise secured thereon. A similar seat 27 having its ends 28 secured to the opposite frame sections 15 and 16, is mounted in front of 80 the cushion 20. Straps 29 and 30 are mounted in front of the seats 25 and 27, respectively, and are secured to the frame members by having their ends 31 and 32 sewed about said frame members.

Each of the sections comprising the boat frame 85 10 has one end formed as shown in Figure 4, and the other end formed as shown on the left hand side of Figure 5. Taking for example the section 13, its one end is conically tapered as shown at 33, and a peripheral slot 34 encircles this end adjacent the conical surface. The hollow passage 90 extending through all of the frame sections is indicated at 35. The adjacent end of frame section 17 which is adapted to be interlocked with the end just described of section 13, has its hollow passage indicated at 35. A pin 36 projects from the end of this passage and is adapted to enter the hollow passage 35 of section 13. A pair of oppositely-disposed resilient fingers 37 having dogs 38 on their free ends are mounted by means of screws 39 on the end of section 17. It is apparent that upon insertion of the pin 36 in the passage 35 of section 13, the dogs 38 will ride up the conical surface 33 until they reach the peripheral slot 34, whereupon they will be forced into engagement with said slot and releasably lock the two sections. As there is no reason to prevent rotation of each individual section of the frame, the slot 34 has been extended completely around 100 on the end of section 13 so that when putting the 105 110

frame together time will be saved by eliminating the necessity of first aligning the dogs 38 with the slots they are adapted to register in.

In the case of the dismountable paddle adapted to be used to propel this boat, it is, however, necessary that the various sections of the paddle do not rotate with respect to each other, and therefore the resilient fingers 44 shown projecting from the central paddle member 41, must be aligned with recesses 42 in the paddle end 40 before these sections will mutually interlock. In order to facilitate separation of the spring fingers 44, the opposite sides of the paddle end adjacent the slots 42 have been flattened as shown at 43 so that the dogs on the ends of the fingers 44 will readily ride up these flattened surfaces. The central pin extending outwardly from the section 41 is indicated at 46, and the spring fingers are shown secured to this section by means of screws 45. It is therefore obvious that in using the paddle after it has been assembled, the paddle end 40 will not rotate with respect to the central section 41. The completed paddle comprises the central section 41 and a paddle end 40 mounted on each end of the central section.

In use the occupant of the boat is seated on either of the seats 15 or 27 and he rests his feet upon the strap 29 or 30, his back resting against the indented side 22 or 23 of the cushion 19 or 20. Obviously, two persons may occupy the boat, and obviously, in constructing such a boat it may be designed for three or more passengers although two would be the most usually desired number.

In order to dismantle the boat for transportation, the two end sections are first removed by re-

leasing the fingers 37 so that the dogs 38 are disengaged from the slot 34, and in a similar manner the other sections are detached from each other. The finished parcel ready for transportation then comprises the two end sections, the middle section including the cushion 20, and the seat sections, all of which may be stacked one upon the other and upon deflation of the various cushions the whole may be united to form a package easily carried by a single person. The paddle is similarly dismantled and may be placed with the pipe sections or carried separately. It is obvious from the above that it is also a simple operation to join the various sections together to reconstruct the boat and the paddle.

Obvious modifications in form and structure may be made without departing from the spirit of the invention.

I claim:

A collapsible boat comprising an endless pipe-like frame divided into sections releasably attached to each other, a plurality of cushions secured to some of said sections, means for releasably interlocking said sections to each other, said means comprising a tapering end on each of said sections, a peripheral slot concentric with the axis of said end adjacent said tapering end, a pin projecting axially from the other end of said section, a resilient spring finger secured to said other end and projecting from the surface thereof substantially parallel with said pin, and a hook on the end of said finger adapted to register yieldably in said slot.

ALFRED BERENDT.
